CLAIM

The ornamental design for a combined adjustable multi-pair shoe drying apparatus with bar for inside a clothes dryer, as shown and described.

DESCRIPTION

FIG. 1 is a bottom perspective view of a combined adjustable multi-pair shoe drying apparatus with bar for inside a clothes dryer, according to the present invention.

FIG. 2 is a top perspective view thereof.

FIG. 3 is a top perspective view showing the claimed design with a single pair configuration with bar.

FIG. 4 is a top perspective view showing the claimed design with a single pair configuration without bar.

FIG. 5 is a front top perspective view of the claimed design outside of a clothes dryer.

FIG. 6 is a bottom rear perspective view thereof.

FIG. 7 is a front view thereof.

FIG. 8 is a rear view thereof.

FIG. 9 is an enlarged detail view of area designated 9 in FIG. 5.

FIG. 10 is a right view of FIG. 8.

FIG. 11 is a left view thereof; and,

FIG. 12 is an exploded view thereof.

The broken lines showing of the clothes dryer are included for the purpose of illustrating environmental structure of the combined adjustable multi-pair shoe drying apparatus with bar for inside a clothes dryer and form no part of the claimed design.

The dashed broken lines shown in FIGS. 5 and 9 indicate cutoff boundaries for the enlarged detailed portion views and form no part of the claimed design.
